UNITED STATES PATENT OFFICE

LE BONSIEUR, OF ELYRIA, OHIO, ASSIGNOR TO THE GENERAL INDUSTRIES COMPANY,
OF ELYRIA, OHIO, A CORPORATION OF OHIO

PHONOGRAPH TURNTABLE

Application filed April 29, 1927. Serial No. 187,502.

My invention relates to an improved sheet metal turntable for phonograph disk records.

An object of my invention is to provide an improved sheet metal turntable which may be produced rigid in construction by a minimum amount of metal, wherein ringing and vibration of the same is subdued.

Another object of my invention resides in the provision of an improved disk record turntable which supports the record at its broader or peripheral portions, thereby eliminating rocking of the record thereon.

Another object of the invention is to secure the appearance of a very rugged turntable with the edge of a soft facing therefor concealed, and appearing to be clamped to the underlying turntable portion.

Another object of my invention resides in the provision of an improved sheet metal turntable requiring a minimum amount of facing material, such as plush, velour or the like, which is quite costly.

Another object of my invention is to provide a turntable faced with soft material whose edges are so positioned relative to the turntable so that they will be protected and not be so exposed as to become scuffed, unravelled, or separated from the turntable.

Another object of my invention resides in the provision of an improved disk record turntable which is attractive in appearance, of light weight, and which is economical to manufacture in large quantities.

These and other objects of my invention and the invention itself will become apparent from reference to the following description of an embodiment thereof, and in which description reference will be had to the accompanying drawings, forming a part of this specification.

Referring to the drawings:

Fig. 1 is a plan view of an embodiment of my invention, the pile fabric covering thereof being partly omitted;

Figs. 2 and 3 are transverse medial sectional views taken on the lines 2—2 and 3—3, respectively, of Fig. 1; and

Fig. 4 is an enlarged fragmentary sectional view taken on the line 4—4 of Fig. 1.

Referring to all the figures of the draw-

ings, in all of which like parts are designated by like reference characters, my improved disk record turntable preferably comprises a central boss or hub 1 which is formed of a light metallic casting and has a centrally disposed bore 15 into which the turntable rotating spindle or shaft may project. The hub is provided with an annular flange 3 having apertures therein for the reception of rivets which may be upset to rivet the hub to the central portion of the turntable disk 2, concentrically about the central aperture 13 of the disk. The turntable disk 2 is preferably formed from pressed sheet metal, the central portion 18 thereof being counter-sunk at 35 to provide a central recess 36 adjacent the disk aperture. The recess 36 is of sufficient depth that the rivets will not project above the top surface 34 of the disk and contact with a record when placed upon the turntable. Such a construction eliminates the possibility of the record rocking or tilting on the turntable due to a central projection such as the rivets.

A plurality of concentrically disposed grooves 6 and 7 and 8 are formed by die stamping the same in the disk and a plurality of radially extending grooves 5 which intersect and join at 18 to the grooves 6, 7 and 8 are also stamped in the turntable disk and provides a turntable which is rigid and stiff and wherein vibration or ringing of the turntable is effectively subdued. The radially extending grooves terminate at 9 beyond the concentric groove 8 and adjacent the annular groove 20 disposed adjacent to the peripheries of the disk.

As best shown in Fig. 4, an annular flange 4 is formed in the disk periphery and depends from a flattened bead portion 12 of the disk, which flattened bead is the most elevated portion of the disk. The inner edge of the flattened bead is pressed downwardly at 23 on a plane parallel with the annular flange 4 to provide an upright wall 24 of the angularly shaped annular groove 20. The opposite wall of 25 of the groove is pressed downwardly on a curve from the disk top surface 14 at 28 and joins at the base of the groove 10 with the wall 24 to form a pointed groove 100.

bottom into which the peripheral edge of a velour disk cover, soft facing 11, or the like, may extend wherein it is secured by means of a shellac or other suitable adhesive substance applied to the disk.

5 The exterior surface of the annular depending flange and the exterior surface of the flat bead portion of the disk and a portion of the side wall 24 thereof may be nickel-plated to 10 present the uncovered metallic portions of the disk of attractive appearance.

15 The disk 2 is slightly convex in its transverse dimensions from its periphery to the center thereof whereby a record placed upon the disk will be supported flat thereon to 20 avoid rocking of the same.

25 The soft surface or velour 11 may be applied to the disk surface 14, by first applying a coating of adhesive substance, such as glue or shellac, thereon, and then applying the soft surface 11 to the disk while the adhesive substance is still plastic and pressing the same onto the disk radially outwardly from the central eyelet 14. The edge of the soft surface is disposed, when so applied, over the concentric groove 20, which groove has been coated with the adhesive substance prior to placing the soft surface on the disk.

30 A tool 31, such as is indicated in Fig. 4 of the drawings, is then rolled in a circular path, exerting an outward force on the same, along the edge of the cover and forces the same into pointed recess of the groove 20 and onto the inclined wall thereof which exerts an outwardly pull on the soft surface due to the inclined curved wall 25 of the groove with the result that the cover is stretched into a flat or smooth surface on the disk. The edge of the cover is thus forced into intimate engagement with the surface of the annular wall 24 35 of the groove, and being pressed down by the tool 31 before the adhesive has set, will adhere to said wall and the selvage will not be visible.

40 45 The cover when so applied to my improved disk record turntable, simulates a disk having a cover thereon and a detachable annular ring portion mounted on the periphery of the disk with the edge of the soft facing concealed under the annular ring and compressed thereunder.

50 55 At the same time, the edge of the soft surface will not be exposed to contact with extraneous objects whereby it may be unraveled and gradually separate from the disk in use. By making the disk in one piece economy in manufacture is accomplished without sacrificing sturdiness and attractive appearance.

60 65 Having thus described my invention in a specific embodiment, I am aware that numerous and extensive departures may be made from the embodiment herein illustrated and described but without departing from the spirit of my invention.

I claim:

1. A phonograph disk record turntable, comprising a pressed sheet metal disk, a supporting hub therefor, a disk of relatively soft surface material secured to and covering the major portion of the disk, said metal disc being formed with concentric spaced folds, the outer one of said spaced folds providing an annular groove in the metal disk adjacent its periphery dividing the metal disk into a relatively narrow border and inner portions into which the edge of the soft surface extends, said edge closely engaging the outer wall of the groove and depressed below the level of the turntable border portions, and a depending annular reinforcing flange on the periphery of the disk.

2. A turntable comprising a sheet metal disk having a groove having an inwardly disposed slightly upwardly inclined relatively wide annular wall and an annular outer wall extending relatively abruptly upward; dividing its upper surface into inner and a relatively narrow border surface portions, a layer of soft material affixed to the inner surface portion and extending into the groove, being affixed and secured to the inner wall of the groove and with its edge disposed in close adherent engagement with the opposite wall thereof, and depressed below the said border surface.

In testimony whereof I hereunto affix my signature this 8th day of April, 1927.

LE BONSIEUR.
